UNITED STATES PATENT OFFICE.

OLIVER H. HICKS, OF CHICAGO, ILLINOIS.

PACKAGE OF TOILET-PAPER.

SPECIFICATION forming part of Letters Patent No. 352,951, dated November 23, 1886.

Application filed October 28, 1885. Serial No. 181,189. (No model.)

To all whom it may concern:

Be it known that I, OLIVER H. HICKS, of Chicago, in the county of Cook and State of Illinois, have invented certain new and useful 5 Improvements in Packages of Toilet-Paper; and I do hereby declare the following to be a full, clear, and exact description of the same, reference being had to the accompanying drawings, forming a part of this specification, and 10 to the figures and letters of reference marked thereon.

My present invention relates to an improvement upon that for which Letters Patent of the United States were granted me on the 1st 15 day of September, 1885, No. 325,410; and it consists in an improved form of bundle constructed to permit of the more ready separation of the sheets of paper, as will be described hereinafter.

20 In my prior patent referred to the bundle of paper employed consisted of one or more lengths of thin paper wound in the form of a continuous band, and having its ends parallel to each other, so as to produce sheets of equal width from end to end; but in my present invention I so form the bundle as that when compressed or flattened its ends shall converge toward one or both sides, which convergence has the effect of producing sheets narrowed at 25 one end, or both, the narrow portions being weaker and offering less resistance than the wider portions, and constituting points at which to readily separate the sheets.

30 In the accompanying drawings I have illustrated my improved form of bundle.

Figure 1 shows the mode of tearing off the sheets. Fig. 2 is a side view of one of the bundles; Fig. 3, a view of a modification, and Fig. 4 is a view showing the manner of cutting the large roll of paper so as to form the 35 small bundles.

In the manufacture of these bundles I preferably wind a continuous web of paper of full width upon a mandrel of suitable size, with or

without the interposition of the thick paper 45 core *a*, and when the band has attained a sufficient thickness remove it from the mandrel, flatten it into the oval or oblong shape shown in the drawings, and cut it on the dotted lines shown in Fig. 4, producing a bundle of paper 50 of convenient size, with one of its sides narrower than the other, as shown. The sheets can now be separated from the roll by the operator's holding the paper in his left hand, with the smaller end uppermost, as indicated 55 in the drawings, and tearing off a sheet, the separation taking place at the top of the band. As soon as a sheet is separated the end of the next will drop down and hang in convenient position to be in turn grasped and severed. 60

In Fig. 3 is shown a modified form of roll tapering toward both sides, which can be employed, if desired; but I prefer the one shown in the other figures. The sheets removed are intended to be doubled, and are of a shape 65 more convenient than rectangular sheets. Breadth at one end only is requisite, and the narrowing of the other end, while of no disadvantage, effects an economy in paper. This form of bundle may be mounted in a fixture such as 70 shown in my application for patent filed July 17, 1885, Serial No. 171,895, or it may be used detached from a fixture, as described.

I do not desire to claim herein, broadly, a roll of paper weakened at one or more points, 75 as I have made that invention the subject-matter of another application filed by me on the 17th day of July, 1885, Serial No. 171,894.

I claim as my invention— 80
As a new article of manufacture, a roll of toilet-paper having converging ends, substantially as described.

OLIVER H. HICKS.
